Primary Examiner — Philip S Hyder(74) *Attorney, Agent, or Firm* — Heslin Rothenberg Farley & Mesiti PC; Kristian E. Ziegler, Esq.(57) **CLAIM**

I claim the ornamental design for a tile positioning device, as shown and described.

DESCRIPTION

FIG. 1 is an elevational front perspective view of the tile positioning device in accordance with my new design;

FIG. 2 is a front view thereof;

FIG. 3 is a cross-sectional view thereof as indicated in FIG. 2;

FIG. 4 is a back view thereof;

FIG. 5 is a left side view thereof;

FIG. 6 is a right side view thereof;

FIG. 7 is a top view thereof; and,

FIG. 8 is a bottom side view thereof.

The broken lines in the figures represent environmental structure and form no part of the claimed design.

1 Claim, 7 Drawing Sheets(56)
